Des. 180,133

Patented Apr. 23, 1957

180,133

CHILD'S STOOL

Haskell Benson, Chicago, Ill., assignor to The Benson Company, Inc., Chicago, Ill., a corporation of Illinois

Application December 20, 1955, Serial No. 39,401

Term of patent 14 years

(Cl. D15—8)

FIG. 1

FIG. 2

FIG. 3

FIG. 4

Fig. 1 is a side elevation, viewed from the left, of a child's stool showing my new design;

Fig. 2 is a front view thereof;

Fig. 3 is a posterior view thereof; and

Fig. 4 is a top plan view thereof.

I claim:

The ornamental design for a child's stool, substantially as shown.
